UNITED STATES PATENT OFFICE.

LOUIS BASKIN AND MAX STERNBERG, OF CHICAGO, ILLINOIS.

DESIGN FOR A COMBINATION ASH TRAY AND LAMP CAP.

Application filed December 13, 1926. Serial No. 20,041. Term of patent 7 years.

To all whom it may concern:

Be it known that we, LOUIS BASKIN and MAX STERNBERG, citizens of the United States, residing at 1632 South Sawyer Avenue and 243 East Huron Street, respectively, in Chicago, county of Cook, and State of Illinois, have invented a new, original, and ornamental Design for Combination Ash Tray and Lamp Cap, of which the following is a specification, reference being had to the accompanying drawing, forming part thereof.

In the drawing Fig. 1 is a face view of our new design for combination ash tray and lamp cap;

Fig. 2 is a top plan view of Fig. 1; and Fig. 3 is a right side elevation of Fig. 1.

We claim:

The ornamental design for a combination ash tray and lamp cap as shown.

MAX STERNBERG.
LOUIS BASKIN.
